UNITED STATES PATENT OFFICE.

WALTER W. BAILLIE, OF WARREN, OHIO.

CINDER CLAMP.

Application filed July 2, 1925. Serial No. 41,118.

This invention relates to improvements in grapples, and is more particularly adapted to a clamp for grasping and removing cinders, or clinkers from furnaces, grates, or 5 stoves.

One of the important objects of the present invention is to provide a tool of the above mentioned character which includes a tubular member having a stationary jaw on the lower end thereof, an elongated rod extending longitudinally through the tubular member and being adapted for slidable movement therein having a jaw carried by its lower end and adapted for cooperation 10 with the stationary jaw in clamping and holding the cinder or clinker which is to be removed.

A further object is to provide a tool of the above mentioned character wherein means 20 is provided for automatically returning the movable jaw to its normally open position when the actuating means for the rod and movable jaw is released.

A still further object is to provide a tool 25 of the above mentioned character which is simple in construction, inexpensive, strong and durable and further well adapted to the purpose for which it is designed.

Other objects and advantages of the invention will become apparent from the following description taken in connection with the accompanying drawing.

In the accompanying drawing forming a 35 part of this application and in which like numerals designate like parts throughout the same:—

The figure represents a vertical sectional view of the cinder clamp embodying my invention, with parts being shown in elevation.

In the drawing, wherein for the purpose of illustration is shown the preferred embodiment of my invention, the numeral 1 designates an elongated tubular member, the 45 respective ends of which are externally threaded. Adapted to be detachably supported on the lower end of the tubular member is the stationary jaw 2, it being formed of a suitable piece of metal. The upper end thereof is bent laterally as illustrated at 3, and the same is provided with the suitable opening for permitting the lower end of the tubular member to extend therethrough, suitable clamping nuts 4 and 5 being threaded on the tubular member and disposed on opposite sides of the laterally ex-

tending portion 3 for securing the jaw against accidental displacement from the lower end of the tubular member. The opposite end of the piece of metal from which the stationary jaw is formed is also bent laterally as illustrated at 6 and is disposed below the lower end of the tubular member in the manner clearly illustrated in the drawing.

A handle 7 is arranged at the opposite end of the tubular member, the same having its intermediate portion disposed substantially horizontal as illustrated at 8, and the same has an opening formed therein whereby it 70 may be disposed over the upper end of the tubular member, suitable clamping nuts 9 and 10 being threaded on the upper end of the tubular member on opposite sides of the intermediate portion of the handle for 75 detachably securing the same in position thereon. The forward end of the handle 7 is bent upwardly as illustrated at 11, and the purpose thereof will hereinafter be more fully described.

Extending longitudinally through the tubular member 1 and adapted for slidable movement therein is the elongated rod 12, the same being of greater length than the tubular member, the lower end of said rod 80 extending through a suitable opening provided therefor in the laterally extending lower portion 6 of the stationary jaw 2.

The movable jaw designated generally by the numeral 13, and which is secured on the lower portion of the rod 12 is formed of a single piece of metal, the same being bent back upon itself intermediate its ends, the free end portions of said piece of metal being secured to a suitable block 14, the latter 85 in turn being supported on the rod 12, and fastened as at 15. A coil spring 16 encircles the lower portion of the elongated rod 12 and is disposed between the laterally extending portion 6 of the jaw 2, and the movable jaw 13 as is clearly illustrated in the drawing. The coil spring 16 provides a means for normally holding the movable jaw away from the stationary jaw.

A trigger 17 is pivotally secured at its 105 forward end to the upper end of the upwardly extending portion 11 of the handle 7, as at 18. The intermediate portion of the trigger is operatively connected to the upper end of the elongated rod 12 which extends 110 above the upper end of the tubular member 1 through the medium of the link 19.

The operation of my improved cinder clamp may be briefly stated as follows: Normally, the parts are arranged as shown in the drawing, and it is obvious that when the trigger 17 is pressed downwardly, the rod 12 will move downwardly within the tubular member 1, simultaneously causing the movable jaw 13 to move into coacting relation with the stationary jaw against the tension of the coil spring 16 whereby the cinder or clinker will be clamped between the jaws, and held therebetween to permit the same to be removed from the stove, grate, or furnace. As soon as the trigger is released, the coil spring 16 will force the movable jaw 13 upwardly, as well as the elongated rod 12 so that the movable jaw is returned to its normal position out of cooperating relation with the stationary jaw.

20 A tool of the above mentioned character will save considerable time and labor in removing cinder and clinkers from a stove or furnace, and furthermore will at all times be positive and efficient in carrying out the purposes for which it is designed. The simplicity of the present device enables the same to be constructed at a very low cost, yet being strong and durable.

30 While I have shown the preferred embodiment of the invention it is to be understood that minor changes in the size, shape and arrangement of parts may be resorted to without departing from the spirit of the invention and the scope of the appended 35 claims.

Having thus described the invention, what I claim as new and desire to secure by Letters Patent is:—

40 1. A tool of the class described comprising an elongated tubular member, a stationary jaw carried by the lower end thereof, an

elongated rod extending longitudinally through the tubular member and adapted for slidable movement therein, the lower end of said rod extending through the stationary 45 jaw, a jaw carried by the lower portion of the rod, means for moving said rod downwardly whereby the jaw carried on the lower portion thereof is brought into coacting relation with the stationary jaw, and 50 a coil spring encircling the lower portion of the rod and disposed between the stationary jaw and the movable jaw for forcing the latter upwardly to its normal position when the aforementioned means is released. 55

2. A tool of the class described comprising an elongated tubular member, a stationary jaw carried by the lower end thereof, an elongated rod extending longitudinally through the tubular member and adapted 60 for slidable movement therein, a jaw carried by the lower end of the said rod, a stationary handle at the upper end of the tubular member, said stationary handle having its intermediate portion disposed horizontally and 65 secured on the upper end of the rod, the end portions of the handle being bent upwardly in divergent relation, a trigger pivotally secured at its outer end to the upper end of one of the upwardly disposed ends of the 70 handle, the other end of the trigger adapted for cooperation with the other upwardly disposed end of the handle, a link pivotally connecting the intermediate portion of the trigger with the upper end of the rod where- 75 by the rod and the jaw carried by the lower end thereof are moved downwardly when the trigger is actuated whereby the movable jaw is swung into coacting relation with the stationary jaw. 80

In testimony whereof I affix my signature.
WALTER W. BAILLIE.
